UNITED STATES PATENT OFFICE.

STEPHEN R. PARKHURST, OF NEW YORK, N. Y.

IMPROVEMENT IN CARDING-MACHINES.

Specification forming part of Letters Patent No. 32,380, dated May 21, 1861.

To all whom it may concern:

Be it known that I, STEPHEN R. PARKHURST, of the city and State of New York, have invented, made, and applied to use certain new and useful Improvements in Feed-Rollers for Carding-Machines, &c.; and I do hereby declare that the following is a full, clear, and exact description of the construction and operation of the same, reference being had to the annexed drawings, making part of this specification, wherein—

Figure 1 is a vertical section of my improved rollers as in place for use. Fig. 2 is a plan showing a portion of said rollers, and Fig. 3 is a section of one of the feed-rollers in larger size than in Fig. 1.

Similar marks of reference denote the same parts.

The ordinary rollers used for carding or picking machines tend to compress and hold the cotton, wool, or other fibrous material as it is fed into the machine, so that instead of said fibrous material being opened, loosened, and evenly spread on the cylinder of card or other teeth the same passes in lumps or bunches, which not only prevents the fibers being evenly spread on the cylinder, but also tends to envelop and retain any foreign matter in said fiber and render it more difficult to remove the same.

The nature of my said invention consists in an improved construction of feed-rollers formed of serrated or comb plates that loosen and open the fiber as passed from the apron to the cylinder, and do not compress, injure, or cause lumps in the mass of fibrous substance, but spread the same evenly on the cylinder; and this construction of rollers is adapted to and may be used with almost all kinds of carding, picking, or other machines for treating the unspun fibers.

In the drawings I have represented a cylinder *a* of card-teeth; but the same may be covered with any other kind of teeth, and represent any portion of a carding, picking, or other machine to which my invention may be applied.

b and *c* are the feed-rollers, and *d* is a vibrating brush, to which parts my invention relates.

The roller *b* is formed in a peculiar manner by the use of cross-plates serrated at their ends, which in consequence of their peculiar

construction and arrangement do not require any center shaft for forming said roller. I take strips of metal of the width required and cut or otherwise form on the same teeth *1* and place said strips together, crossing each other, and secure them together until I form a complete cylinder. I have found the proportion and arrangement of the strips shown in Fig. 3 to be the most convenient. Each strip is formed with two holes, and I provide eight rods *2* secured at one end to the metallic head on the journals of the roller. I then commence and thread on the plates or strips *g h i k* in succession, crossing each pair of plates at right angles to each other, and then placing the next pair diagonally to the previous ones on the intermediate pairs of rods, and continue threading on these strips or plates in this manner until a complete roller is made up of the same. I then pass over the rods the end piece of the roller attached to the journal and compress the plates powerfully, so as to bring the surfaces to each other, and screw, rivet, or otherwise securely retain the rods *2* to said end, which rods hold the said ends of the rollers and plates firmly together. Care must be taken to have the whole of the parts central with the journals before end compression. This may be accomplished by a pipe or other device to receive the roller. It will be evident that by this arrangement of plates or strips the center of the roller is a compact mass, obviating the necessity of a shaft, while the teeth on the edges are kept apart, there being the thickness of the intervening plates between the ranges of teeth longitudinally of the roller, and the whole surface is a mass of comb-plate teeth and intervening spaces.

The plates shown in Fig. 3 are about the actual size and shape that I make use of. The same may, however, be slightly varied either in size or shape.

The feed-roller *c* is to be formed with longitudinal ribs, and the edges of these ribs may or may not be formed with notches or teeth. These two rollers *b* and *c* are to be set in suitable journals, boxes, or bearings, and geared together, so as to revolve at the same or slightly-different speed, and the roller *c* should receive a sliding end motion in its journals. For this purpose I have represented the grooved zigzag cam *4* on the shaft (of *c*) to

give the end motion as said cam runs against the fixed piece 5.

The brush *d* is to be made of wire or other material, and the bar to which it is attached is to be sustained in any suitable supports, so that a vibrating motion can be given to the same. For this purpose I have represented the zigzag cam 3 on the shaft of the cylinder *a*, and a lever *e*, between this cam and brush, communicates a vibrating movement to the brush *d* for the aforesaid purpose. The fibrous material is to be supplied by any suitable belt. The red lines, Fig. 1, represent the position thereof.

The operation of this mechanism is as follows: The roller *b* tends not only to feed in the fibrous material, but the serrations forming the surface thereof penetrate any lumps, tending to loosen them. This feed-roller, however, does not become clogged, because the shape of the teeth allows the fibrous matter to draw off easily, and the teeth of said roller are not injured by any lumps, burrs, or other foreign or hard substances. The roller *c* acts in conjunction with the roller *b* to loosen and comb the fibrous mass as passed into the machine, (instead of compressing it,) because the longitudinal ribs only detain the fibers and prevent their being drawn off, too fast by the cylinder *a*, and burrs or lumps will be held back behind these ribs, which move slowly in comparison with the surface of the cylinder *a*. Besides this, the end motion of the roller *c* tends to separate, loosen, and evenly distribute the fibrous mass. The brush *d* tends to lay the fibers upon the teeth of the cylinder *a* with still greater uniformity, because its vibration is to be rapid, and this brush causes the teeth to take a firmer hold upon the fibers by slightly detaining them, and this operation does not tend to embed any foreign substance in the teeth; hence

the fibers are in the best possible condition for any of the usual operations of cleaning, carding, or picking.

I have represented my feeding-rollers as acting together and with the brush, as jointly they lay the fibers of wool, cotton, or other material in the best position for the subsequent operations; but it will be evident that each respective part has peculiarities of construction or operation. I therefore do not limit myself to the combined use of the parts, but intend to use them either jointly or separately or combined with other well-known parts.

It will be evident that a disk might be used between each pair of plates for keeping the teeth more or less distant from each other, and the particular shape of the teeth or serrations may be varied according to the character of fiber, and if found advantageous the roller or cylinder *b* may not be firmly compressed endwise, but left with a slight amount of springing movement.

What I claim, and desire to secure by Letters Patent, is—

1. The employment of a series of metallic strips or plates with serrations on their edges placed crosswise of each other, substantially as set forth, to form a feed roller or cylinder adapted to carding and similar machines, as specified.

2. In a carding or similar machine, forming the upper feed-roller *c* with a series of ribs, in the manner specified, for more effectually detaining lumps or foreign substances as they pass to a carding or toothed cylinder, so as to cause said lumps to be opened or separated, as specified.

S. R. PARKHURST.
